FASTENING-INSERTING MACHINE

Lester S. Macdonald, Beverly, Mass., assignor to
 United Shoe Machinery Corporation, Paterson,
 N. J., a corporation of New Jersey

Application February 1, 1933, Serial No. 654,670

29 Claims. (Cl. 1—32)

This invention relates to machines for inserting fastenings, being especially applicable to apparatus for attaching heels to shoes, as by nails driven from the inside of the shoes through the heel-seats into the heels.

An object of the invention is to so organize the machine that it readily may be arranged for the insertion of the fastenings in accordance with different designs. Though not limited to such an application, an important purpose of the invention is to provide for the positioning of inserting instrumentalities which are arranged to drive fastenings into the work in an inclined direction.

As a feature of the invention leading to the attainment of this object, there is combined with a work-support, as a jack for shoes, a carrier movable upon the support, a tube or like member mounted to oscillate on the carrier, which tube may guide a fastening-inserting or driving member movable in it, and means arranged to vary the position of the carrier upon the support. As illustrated, the inserting member is movable by an actuator, which preferably takes the form of a plunger co-operating with the support, and the guide member is inclined to the direction in which this actuator moves. With a plurality of these guide-tubes, their inclination causes them to converge toward the work-engaging surface of the support, while there co-operates with them, as by engagement with their carriers or otherwise, means for moving the converging ends toward and from one another. More specifically, there is employed for the attachment of heels to shoes a jack in which a plunger reciprocates longitudinally, carriers movable upon the jack, a driver-tube, with its contained driver, pivoted upon each carrier so it may be inclined in the direction of movement of the plunger, and a controlling member movable upon the jack and acting upon all the carriers. As herein disclosed, the controlling member communicates movement to a carrier, which in turn is connected to another carrier to cause its actuation. The first of these carriers may consist of a slide movable upon the jack and the second of a lever pivoted upon said jack. By such an arrangement, the relation of the tube or tubes to the work may be varied for different sizes of shoes and styles of heels without disturbing the position which permits them to drive nails through the heel-seat of a shoe into a heel from points relatively close to the periphery of said heel, and so inclined inwardly that a tight rand-crease is obtained with-

out danger of the nails breaking through the heel-wall.

A further feature of the invention has to do with the supplying of fastenings to the work-support. Here, a transferring or loading device has fastening-holding tubes or like means movable upon it to different positions, together with a member movable to position all the holding means, and means at the support for actuating the positioning means. When such a transferring device is associated with a work-supported or organized as just outlined, the control of the positioning means may be exercised by the means which moves the carriers or the driver-tubes. Thus, however the carriers or tubes may be adjusted for a chosen inserting design, the positioning of the fastening-holders at the loading device may be correspondingly obtained so accurate delivery will be made, this being accomplished by relatively simple mechanism. The holding tubes at the loader, for nails or other fastenings, are preferably forced yieldingly to a normal position, as by a spring, which may act upon a positioning member furnished by a plate provided with inclined slots co-operating with intersecting slots in the loader and in which the tubes are movable. If automatic adjustment of the loader-tubes to agree with the support- or jack-tubes is not desired, the positioning means may be fixed against movement upon the loader so the spring is rendered ineffective.

The accompanying drawing shows a particular embodiment of the invention,

Fig. 1 being a broken side elevation of the jack and loader;

Fig. 2, a broken top plan view thereof;

Fig. 3, a perspective view of the driver-tubes of the jack with their more closely associated elements, these being in part separated from one another; and

Fig. 4, a perspective view of the adjusting plate for the loader-tubes.

This invention may be applied to apparatus of the character of that disclosed in Letters Patent of the United States, No. 1,867,560, Benjamin, July 19, 1932. Of such a machine, there is only shown herein the work-supporting jack J and the reciprocating loader L for delivering nails to said jack. The manner of supporting the jack and actuating its drivers and of guiding and reciprocating the loader may be as in the just-mentioned patent. In the body 10 of the jack, a plunger 12 is arranged to reciprocate vertically, and has, at its upper end, a driver-plate 14 in sockets in which nail-drivers 16 are mounted by cylindrical

60

110

ends 18 for oscillation. Each driver, there being five illustrated, is guided within a tube. Of these, the rear tube 20 may be pivoted upon the jack-body for universal movement by a more or less 5 globular head 22. The remaining tubes, 24, 24 for the side nails and 26, 26 for the breast-nails, are similarly pivoted by heads 22 upon movable carriers, as will be described. The mountings of all the driver-tubes and their points of connection to the driver-plate 14 are so arranged that said tubes are inclined with reference to the direction of reciprocation of the actuating plunger 12, they converging inwardly to a top-plate 28 of the jack, which plate is engaged by the heel-seat-end of the insole of a shoe to be operated upon. The openings in the heads of the tubes lie in close proximity to the upper surface of the plate, the head of the tube 22 occupying a circular opening 30, while the tubes 24, 24 are movable in lateral slots 32, and the tubes 26 in rearwardly-extending slots 34. Secured to the front of the jack-body, within the hollow portion, is a bracket 36, in the upper rearward extension of which is an opening 38 to receive a pivot-pin common to two carrier-arms 40, 40. The rear extremities of these arms are provided with vertical sleeves 42 in which are formed sockets for the reception of the heads 22 upon the driver-tubes 24. These heads project from the upper ends of the sleeves to enter the slots 32 in the top-plate, and the lower portions furnish sufficient clearance to permit free oscillation of the tubes as the plunger 12 reciprocates the drivers 16. To movably support the rear tubes 36, slides 44 are arranged to travel in ways 46 upon opposite sides of the bracket 36 and have sockets in which these tubes are mounted. The arms and slides are preferably simultaneously movable by a controlling member common to all 30 and consisting of a slide 48. This slide 48 is shown as divided to extend at opposite sides of the bracket 36 beneath the lower ways 46, and is threaded at 50 to receive a screw 52 rotatable upon the front of the jack-body and passing through an opening 53 in a bracket. By turning the screw the slide 48 may be shifted transversely of the jack. From the forwardly-extending arms of the slide 48 rise projections 54, 54 which enter openings 56 in links 58, articulated at 60 to the respective slides 44. The slides have extensions 62 at their inner sides in which are horizontal cam-slots 64, facing oppositely or toward each other. Entering these slots are pins 66 projecting oppositely from the arms 40. In using this adjusting means for the driver-tubes, the operator, when the nailing design is to be changed, rotates the screw 52 in one direction or the other. The supporting, guiding and connecting means for the tubes, as just described, are so designed that as the controlling slide 48, acting through the links 58, moves the slides 44 and these, through the slots 64 and projections 66, swing the arms 40 about their pivot, the openings of the tube-heads 22 all follow paths in which lie the points of insertion of the nails for all designs. This occurs without disturbance of the connections between the drivers 16 and the plate 14, said drivers simply oscillating about their ends 18 to assume different angular positions. Similarly, as the plunger rises and falls in its operating strokes for the insertion of the nails held in the tubes on the upper ends of the drivers, an oscillation of both the drivers and tubes is permitted by virtue of their pivotal connections. 70 The loader L has its block 70 carried upon one side of a slide-bar 72, which is reciprocated by power applied to a rack 74 upon its under side. The loader thus travels, as in the Benjamin patent, from a nail-receiving position beneath a distributor (not illustrated) to a nail-delivering position over the jack J. The nails are contained during this transfer in tubes 76, corresponding in number and position to the jack-tubes. The rear tube occupies an opening 78 in a supporting plate 80 secured upon the upper surface of the loader-block. The side and rear tubes lie in slots 82 in this plate. They all have heads 84 which rest upon the upper surface of the plate. Movable between the plate 80 and the body of the loader-block is a positioning plate 86 which is cut away to clear the rear tube and has slots 88 intersecting the slots 82 and receiving the tubes 76. The plate 86 has a forward extension 90 with a perforated abutment member 92 rising from its end. Through an opening in this member passes a horizontal spindle 94 fixed in the front of the loader-block. The member 92 is shown as divided, with the parts capable of being drawn together by a screw 93 so the plate 86 may be fixed in position upon the block 70. A spring 96 surrounds the spindle between the block and the plate member 92, urging the plate 86 to a normal position in which the camming effect of its slots 88, in co-operation with the cross-slots 82 of the supporting plate, causes the tubes to be forced out to positions corresponding to the maximum nailing design. If the plate 82 is moved rearwardly against the force of the spring, the two sets of plate-slots co-operate to shift the tubes inward to extreme positions which may correspond to the minimum nailing design. These maximum and minimum settings, and those for designs between them, may be automatically governed by the tube-controlling mechanism of the jack J. For this purpose, the extension 90 of the positioning plate 86 has a lateral projection 100 to which is attached a rearwardly extending arm 102. At the end of this arm is a depending, inwardly turned finger 104. For any setting of the tubes in the jack less than the maximum design, the finger 104 may contact with an upward projection 106 at one side of the tube-controlling slide 48. This contact will hold the plate 86 against movement while the loader completes its travel over the jack. By properly proportioning the positioning elements of the loader, this may be caused to cam the tubes 76 to positions corresponding to those of the jack-tubes, with the result that when the loader comes to rest the two sets of tubes will be in registration. During the advance of the loader, the nails in the tubes will have been supported with their heads resting upon a shutter 108 pivoted beneath the block 70. A latch 110 at this time retains the shutter thus closed against the tension of a spring 112, joining the latch and shutter. To release the nails for delivery to the jack-tubes, when the loader-tubes are alined with them, the latch may be tripped by engagement with the rear of the jack. It may be reset during its return beneath the distributor by contact of the plate with a fixed element, which is not indicated in the drawing. 110 Generally, the operating procedure is as in any inside heeling machine, as that of Benjamin. The arrangement of jack-tubes in a nailing design best suited to the work to be operated upon may be obtained by manipulation of the screw 52, the setting being made without interference with the inclined relation of the tubes and the contained drivers. Contact between the loader ele- 115 120 125 130 135 140 145 150

ment 104 and the jack element 106 will automatically cause the loader-tubes to conform to the chosen setting of the jack-tubes. If the operator prefers to adjust the loader-tubes manually to a particular design, he may do so by moving the plate 86 when the loader is in its delivering position until the tubes 76 are alined with the jack-tubes, and then secure the plate by clamping the block 92 upon the guiding and spring-retaining spindle 94 by the action of the screw 93.

Having described my invention, what I claim as new and desire to secure by Letters Patent of the United States is:

1. In a fastening-inserting machine, a work-support, a carrier movable upon the support, a fastening-receiving tube mounted to oscillate upon the carrier, a fastening-inserting member reciprocable in the tube, and means arranged to vary the position of the carrier upon the support.

2. In a fastening-inserting machine, a work-support, an actuator movable in co-operation with the support, a carrier movable upon the support, a guide member movable upon the carrier and being inclined to the direction of movement of the actuator, a fastening-inserting member situated in the guide member and connected to the actuator, and means arranged to vary the position of the carrier upon the support.

3. In a fastening-inserting machine, a work-support, an actuator movable in co-operation with the support, a carrier movable upon the support, a guide member mounted to oscillate upon the carrier and being inclined to the direction of movement of the actuator, a fastening-inserting member situated in the guide member and connected to the actuator, and means arranged to vary the position of the carrier upon the support.

4. In a fastening-inserting machine, a work-support, a carrier movable upon the support, a fastening-receiving tube mounted upon the carrier, there being a universal joint connecting said tube and carrier, a driver reciprocable in the tube, and means arranged to vary the position of the carrier upon the support.

5. In a fastening-inserting machine, a work-support, a plurality of guides converging toward the work-engaging surface of the support, a fastening-inserting member operating in each guide, and means co-operating with the guides at the converging ends for moving said ends toward and from one another.

6. In a fastening-inserting machine, a work-support, a plurality of guides, a carrier individual to each guide and in which said guide is movable, said carrier being movable upon the support, means common to the carriers for moving them, and a fastening-inserting member movable in each guide.

7. In a fastening-inserting machine, a work-support, an actuator reciprocable therein, fastening-inserting member pivoted to oscillate upon the actuator, tubes in which the members operate and which are mounted to oscillate therewith, and means engaging the ends of the tubes opposite the actuator for moving them toward and from one another.

8. In a fastening-inserting machine, a work-support, an actuator reciprocable therein, fastening-inserting members pivoted to oscillate upon the actuator, tubes in which the members operate, and members movable at the work-engaging end of the support and upon which the tubes are pivoted.

9. In a fastening-inserting machine, a work-

support, an actuator reciprocable therein, fastening-inserting members pivoted to oscillate upon the actuator, tubes in which the members operate, carriers movable at the work-engaging end of the support and upon which the tubes are pivoted, and means common to the carriers for moving them simultaneously.

10. In a heel-attaching machine, a jack, a plunger reciprocable longitudinally thereof, a carrier movable upon the jack, a driver-tube pivoted in the carrier, a driver operating in the tube and being inclined to the direction of movement of the plunger, and a controlling member connected to the carrier and being movable transversely of the jack.

11. In a heel-attaching machine, a jack, a plunger reciprocable therein, a plurality of carriers movable upon the jack, a driver-tube pivoted in each carrier, a driver operating in each tube, and a controlling member movable upon the jack and acting upon the carriers.

12. In a heel-attaching machine, a jack having a top-plate, a plunger reciprocable longitudinally of the jack, a driver connected to the plunger and inclined thereon toward the top plate, the connected end of the driver being at all times held against movement transversely of the jack, a tube in which the driver operates, and means situated at the jack-top for moving the upper portion of the tube.

13. In a heel-attaching machine, a jack having a top-plate provided with slots, carriers movable upon the jack beneath the top-plate, driver-tubes pivoted upon the carriers and extending into the slots, drivers operating in the tubes, and a member movable transversely of the jack and connected to the carriers.

14. In a heel-attaching machine, a jack, an arm pivotally supported to oscillate about a fixed axis upon the jack, a driver-tube pivoted upon the arm, and a driver operating in the tube.

15. In a heel-attaching machine, a jack, a slide movable upon the jack, an arm pivotally supported to oscillate about a fixed axis upon the jack and connected to the slide, a driver-tube pivoted upon the arm, and a driver operating in the tube.

16. In a heel-attaching machine, a jack, a slide movable laterally of the jack, a driver-tube pivoted upon the slide, and a driver operating in the tube.

17. In a heel-attaching machine, a jack, carriers movable thereon, a driver-tube pivoted upon each carrier, a controlling member movable upon the jack and to which each carrier is joined, and a driver operating on each tube.

18. In a heel-attaching machine, a jack, a carrier-slide movable thereon, a carrier-arm pivoted upon the jack, driver-tubes pivoted upon the slide and arm, a controlling slide acting upon the carrier-slide and the arm, and drivers operating in the tubes.

19. In a heel-attaching machine, a jack, a carrier-slide movable thereon, a carrier-arm pivoted upon the jack, driver-tubes pivoted upon the slide and arm, a controlling slide movable upon the jack, connections to the controlling slide for actuating the carrier-slide, and connections between the carrier-slide and arm for actuating the arm.

20. In a heel-attaching machine, a jack, a plurality of carriers movable thereon, a tube pivoted upon each carrier, a controlling member movable upon the jack, connections to the controlling member for actuating a carrier, connections between the thus-actuated carrier and another car-

rier for actuating the latter, and drivers operating in the tubes.

21. In a fastening-inserting machine, a work-support, a transferring device provided with fastening-holding members movable to different positions and with a member movable to position all of said members, and means at the support for actuating the positioning member.

22. In a fastening-inserting machine, a work-support, a plurality of fastening-receiving guides, a carrier individual to each guide and in which said guide is movable, said carrier being movable upon the support, means common to the carriers for moving them, a fastening-inserting member movable in each guide, and a transferring device provided with fastening-holding members arranged to deliver to the guides and to be differently positioned and with a member controlled by the moving means at the support for positioning the holding members.

23. In a fastening-inserting machine, a work-support, and a transferring device provided with fastening-holding members movable to different positions, a member movable to position all of said members, means for forcing the positioning member yieldably in one direction and means for fixing the positioning member against movement.

24. In a heel-attaching machine, a jack, driver-tubes movable upon the jack, drivers operating in the tubes, a tube-controlling member movable upon the jack, and a loader provided with nail-tubes and a movable positioning member therefor, said loader being movable to deliver nails to the driver-tubes, the positioning member being acted upon by the controlling member.

25. In a heel-attaching machine, a jack, carriers movable thereon, a driver-tube mounted upon each carrier, a controlling member movable upon the jack and acting upon the carriers, a driver movable in each tube, and a loader provided with nail-tubes movable upon it and with a positioning member therefor, said positioning member being movable by contact with the controlling member.

45

26. In a heel-attaching machine, a jack, carriers movable thereon, a driver-tube mounted upon each carrier, a controlling member movable upon the jack and acting upon the carriers, a driver movable in each tube, and a loader provided with nail-tubes movable upon it, a spring holding the nail-tubes in their normal positions and a member for moving said tubes in the opposite direction.

27. In a heel-attaching machine, a jack, carriers movable thereon, a driver-tube mounted upon each carrier, a controlling member movable upon the jack and acting upon the carriers, a driver movable in each tube, and a loader provided with nail-tubes movable upon it, a spring holding the nail-tubes in their normal positions, a positioning member for moving said tubes in the opposite direction and means for securing the positioning member against movement upon the loader.

28. In a heel-attaching machine, a loader comprising a support provided with slots, nail-tubes movable in the slots, a plate movable upon the support and having slots intersecting those of said support and through which the tubes extend, the support and plate being provided one with a projection and the other with a portion through which the projection passes, and means for clamping said portion upon the projection.

29. In a heel-attaching machine, a loader comprising a support provided with slots, nail-tubes movable in the slots, a plate movable upon the support and having slots intersecting those of said support and through which the tubes extend, the support and plate being provided one with a projection and the other with a portion through which the projection passes, a spring surrounding the projection to force the plate in one direction, and means for clamping said portion upon the projection.
